UNITED STATES PATENT OFFICE.

ALONZO B. ELY, OF GROTON, NEW YORK, ASSIGNOR TO CORONA TYPEWRITER COMPANY, INC., OF GROTON, NEW YORK, A CORPORATION OF NEW YORK.

OIL CAN.

Application filed September 28, 1921. Serial No. 503,806.

To all whom it may concern:

Be it known that I, ALONZO B. ELY, a citizen of the United States, and resident of Groton, in the county of Tompkins and State of New York, have invented certain new and useful Improvements in Oil Cans, of which the following is a specification.

This invention relates to improvements in oil cans, and has for its principal objects to provide an oil can which may be easily and economically manufactured, to provide a can which will not roll, to provide a cylindrical can having a removable screw closure cap at one end and a gripping portion at the other end whereby the cap may be tightly screwed on the can body and readily removed, and to provide an oil can of the dropper type which will not leak and is provided with a combined packing seat and dropper scraper so arranged that lubricant scraped from the dropper rod will fall back into the interior of the can body.

To the foregoing and other ends, which will hereinafter appear, the invention consists of the features of construction, arrangements of parts, and combinations of devices set forth in the following description and particularly pointed out in the appended claims.

In the accompanying drawings, in which the preferred embodiment of the invention is illustrated,

Figure 1 is a side elevation of the can; Fig. 2 a vertical section on the line 2—2 of Fig. 1;

Fig. 3 a detail sectional view of the closure cap with the sealing washer or gasket and the dropper rod removed therefrom;

Fig. 4 a sectional view of the sealing gasket;

Fig. 5 a detail vertical sectional view of the open upper end of the can body;

Fig. 6 a side elevation of the lower end of the can body, the view being taken from one side of the can as shown in Fig. 1; and

Fig. 7 an end view of the bottom of the can, illustrating in dotted lines the manner in which the widened and flattened lower end of the can prevents rolling of the can when the can is laid on its side.

The tubular can body 10 is cylindrical in transverse section throughout the major portion of the length of said body and is formed by cutting from commercial metal tubing, of sufficient thickness and rigidity to resist

distortion in the hands, a section of suitable length. One end of the section of tubing is then spun over to form an inwardly extending circumferential flange 11 overhanging the interior of the tubular can body in a plane at right angles to the longitudinal axis of the section of tubing, and the end portion of the can body adjacent said flange is provided with external screw threads 12. The opposite end of the section of tubing is pressed flat between suitable dies to close the bottom of the can body and form a flat gripping portion 13 consisting of two thicknesses of metal pressed closely together and wider than the diameter of the main cylindrical portion of the can body. The can body is drawn into general wedge form by the pressing operation for a short distance above the flat portion 13, as shown at 14, said wedge shaped portion cooperating with the flat portion 13 to afford a substantial non-circular gripping surface which may be firmly grasped between the thumb and fingers to prevent rotary slipping of the can body in the hand while the closure cap 15 hereinafter described is being screwed on or off the open upper end of the can body. The closure cap 15 is formed of relatively heavy metal stock and is cup shaped, said cap being provided with internal screw threads 16 to permit the cap to be screwed down over the upper end of the can. A packing disk or washer 17 of suitable material is forced up into the interior of the closure cap, said disk being of sufficient diameter to be securely retained in the cap by the uppermost screw threads 16 when the cap is removed from the can, said uppermost screw threads biting into the edge of the packing disk which is relatively thick. The exterior of the cap 15 is knurled, as shown at 18, so that the cap may be firmly gripped and will not slip in the fingers during removal or replacement of the cap. The packing disk is adapted to be tightly seated on the flange 11 when cap 15 is screwed on the can body, said flange forming a relatively wide seat around the upper end of the can and cooperating with the packing disk to effectively seal the can.

The head portion of the cap 15 is relatively thick and is provided with a central socket 19 into which the reduced upper end of a dropper rod 20 is tightly driven to rigidly connect said rod to the cap, the cap

forming a hand piece or handle by which the rod may be withdrawn from the can to apply oil or other lubricant. The lower end 21 of the rod is preferably flattened and pointed as shown to facilitate the dropping of oil at the desired point. Flange 11 also serves as a scraper against the inner edge of which the dropper rod may be drawn in removing the rod to remove excess lubricant from the rod, and as said flange overhangs the interior of the can body the excess lubricant will fall back into the interior of the can.

It will be obvious that by providing a can of the construction described the closure cap may be readily tightly screwed down to firmly press the packing against flange 11 and tightly seal the can, and also that the cap may be easily unscrewed even if the can or the hands should be greasy. It will also be observed that the packing will be pressed tightly into the screw threads on the cap and prevent leakage of oil around the packing disk which is provided with a central opening 22 through which rod 20 extends.

The seam or joint between the two flat thicknesses of metal forming the lower end portion 13 of the can is preferably made liquid tight by solder as shown at 23. The solder is preferably applied by dipping the flattened portion 13 first in acid and then in hot solder which creeps between the abutting faces of the flattened thicknesses of metal. The surplus solder is brushed off the sides and lower edge of portion 13 leaving only the solder which lies between the two flat thicknesses of metal.

As the gripping portion at the bottom of the can is considerably wider than the diameter of the main cylindrical portion of the can body it will be obvious that the ends thereof will serve as steps to prevent rolling of the can when laid upon its side, as shown in dotted lines in Fig. 1.

What I claim is:

1. A hand oiler comprising a rigid can body of cylindrical form from its upper end to a point adjacent its lower end, the upper end of said body having a circumferential

flange overhanging the interior of the body 50 and being provided with external screw threads, an internally threaded closure cap for the upper end of the body, a packing in said cap adapted to seat on the upper face of said flange, and a lubricant-applying rod 65 extending centrally through said packing and secured at its upper end to said cap and adapted to be drawn over the inner edge of said overhanging flange as the cap is removed from the body, the lower portion of 60 said body being wedge-shaped.

2. A hand oiler comprising a one-piece sheet metal can body of sufficient rigidity to prevent distortion in the hands of a user, said body being of cylindrical form in transverse section from its upper end to a point adjacent its lower end and having an integral inwardly extending annular flange at its upper end overhanging the interior of the body, the lower end portion of the body having a permanent wedge formation and being wider transversely of the body in one direction than the diameter of the upper portion 70 of the body, said body being provided at its upper end with external screw threads, 75 a closure cap for the upper end of the body having a thick top wall provided with a central socket in its under face, said can having a deep cylindrical skirt portion embracing the upper end of the can body and provided with internal screw threads complementary to the threads on the body, a thick packing disk abutting against the under face of the top wall of the cap and adapted to seat against the upper face of 80 the can body flange, a plurality of the uppermost screw threads on the skirt portion of the cap being embedded in the periphery of said thick disk, and a dropper rod having a driving fit at its upper end in the socket 90 in the top wall of the cap and passing through said packing disk into the can body and adapted to be drawn over the inner edge of the can body flange when the cap is removed from the body.

In testimony whereof I hereunto affix my signature.

ALONZO B. ELY.
